CLAIM

The ornamental design for a nonwoven fabric, as shown and described.

DESCRIPTION

FIG. 1 is a top, plan view of a portion of a nonwoven fabric showing my new design; and,

FIG. 2 is a perspective view, as seen from a top, side vantage, of a portion of a nonwoven fabric within the broken line area, 2, in FIG. 1, it being understood that the broken lines in that view form no part of the claimed design.
